UNITED STATES PATENT OFFICE.

LAUREN S. SCOTT, OF BRISTOL, VERMONT.

GRATE FOR STOVES.

SPECIFICATION forming part of Letters Patent No. 256,923, dated April 25, 1882.

Application filed August 2, 1880. (No model.)

To all whom it may concern:

Be it known that I, LAUREN S. SCOTT, a citizen of the United States, residing in the town of Bristol, county of Addison, and State of Vermont, have invented certain Improvements in Summer Grates for use in Stoves, Ranges, and Heaters, of which the following description, in connection with the accompanying single sheet of drawings, constitutes a specification.

As fire-grates for use in stoves, heaters, and ranges are commonly constructed the interstices for the passage of air and ashes through the horizontal portion thereof are uniform in size and distribution throughout the entire fuel-supporting area of the grate, and no provisions ordinarily exist for contracting or reducing the capacity of the fire-box, unless by devices which in their nature constitute permanent walls, partitions, or structures within the combustion-chamber, and are not under control while hot. By reason of such uniformly open construction of the fuel-supporting portion of the grate it is generally impracticable to hinder or arrest combustion of the fuel remaining in the fire-box after the fire is no longer needed. Again, capacious cooking utensils, like pots and kettles, having deep sinks, and which generally require a deep fire under them, hang so low in the fire-box that it is inconvenient to get sufficient depth of fuel under them to drive the work properly where the fire-box is shallow, and sometimes where it is deep and only a slight or slow fire is needed, and that perhaps only in one end of the fire-chamber, the grate surface will be so low and the fire built thereon will be so far below the surface of the stove or range that it becomes necessary to fill up that end of the fire-box with more fuel than is necessary to do the required work, thereby occasioning waste of fuel and an uncomfortable and unnecessary radiation of heat into the room. Besides, all the unconsumed fuel remaining afire on the grate when the work is done will burn up, if wood, and be lost. These evils are more apparent in the summer season, when irregular and intermittent firings are required, and it is desirable at such times to keep the house or apartments as cool as possible, than in the winter, when constant heat is required

to warm the apartment or room, even when the stove or range is not at work.

To meet and overcome these and other objections which might be urged against the present construction of grates for summer use is the object of this invention; and broadly considered it is accomplished by constructing the fuel-supporting portion of the grate in different horizontal planes in such a way that a sink or basin or basins shall be formed where desired, which will hold a greater volume or depth of fuel than the adjacent or relatively elevated portions of the grate. Such a grate in a fire-box furnishes opportunities for a thin fire on the highest plane of the grate, nearest the top of the stove, when only a light quick fire is needed; or if, on the contrary, a strong, steady, or intense fire is wanted, the sink or lower plane is available. In connection with this grate a hinged partition-plate is used, by means of which the chamber may be divided by simply rolling or turning it up in an erect position, whereby two diminished fire-chambers are constructed, one on either side of such partition-plate, a deep and a shallow one, either or both of which are available for use at the same time. The unconsumed fuel remaining after the use of the fire has ceased is in a great measure prevented from burning entirely out, and is largely saved by constructing some portion of the grate-bottom with very few draft-apertures, so that the coals or embers lying on such portions of the grate will smoulder and ultimately expire for lack of air to support combustion. Such integral part of the grate (which in this case I have located in the central portion of the basin or in the lowest part of the grate) also serves as a receiver, into or upon which all unconsumed fuel can be raked when done using the fire, and draft-dampers are closed, in which the fire will speedily go out when the stove or range is properly arranged for that purpose.

My apparatus will be readily understood by reference to the accompanying drawings, wherein Figure 1 exhibits a perspective view of the upper surface of my improved grate, showing the partition-plate recumbent. Fig. 2 shows a half-section of same with the partition-plate erect. Fig. 3 is a perspective view of the par-

partition-plate detached from the grate, the view being of that side opposite the one shown in Fig. 2. This figure shows the details of the hinge-lugs whereby the plate is attached to the grate when in use.

The construction of the whole apparatus is evident from the drawings with the briefest description. In this case the grate-bed or fuel-supporting plate is constructed in two planes, 10 A being the upper and B being the lower, the difference in their altitude being left to the judgment of the builder. The upper level, A, is uniformly perforated or slotted, as deemed preferable, but the lower level or basin, B, is 15 slightly perforated, as it is not judicious to cut through this bottom under the fire any farther than is really necessary to secure fair combustion when the grate is in use. Therefore the draft-passages for admitting air to this part of 20 the fire are cut through the lateral walls of the basin and may, if desirable, extend slightly into the bottom plate, as seen in Fig. 1. The whole grate is supported in the fire-box of the stove or range by any appropriate means. The provision shown for that purpose in the drawings 25 consists of legs D D, which may be of such length as to reach to the bottom of the fire-box or to rest upon the top of the ordinary fire-grate.

30 The upper level, A, of the grate is provided with a series (or a pair at least) of perforations arranged at proper intervals to receive the hinge-lugs b b, as seen in Fig. 1. The lugs b b are cranked, as shown in Fig. 3, and made with 35 two stop-facets, c c and f f, as shown. These lugs will enter and pass through the holes of the grate A, as seen at b b, Fig. 1, and the stop-facets or ledges are so arranged that when the plate C is erected facets c c will engage 40 with the under side of grate A, and thus prevent the plate from rolling or turning over farther in that direction. When plate C is recumbent, as in Fig. 1, the facets f f in like manner lock under the bottom of grate A, and so prevent displacement of the plate when it would 45 otherwise be disturbed by raking the fire, putting in or taking out fuel or ashes. The partition-plate C is not irremovably connected with or hinged to the perforated plate A, but is constructed so that it can be readily disconnected. 50 It is also susceptible of reversal by transposing its position end for end, in which reversed position, when recumbent, it will lie over and will wholly or partially cover the ember-basin B. When so used it is not material whether its perforations exactly coincide with those of plate B immediately beneath it or not, as a chamber will exist between the two, through 55 which draft will freely circulate.

60 From the foregoing it will be seen that it is not material what the peculiar size or shape of the grate-perforations may be, nor the difference in height of plane A and plane B, nor what the means are to secure the grate in its proper position in the fire-box, provided it is adjusted at a proper elevation.

Several things are to be considered in fitting or adapting the rolling partition-plate C to its position and uses according to the duty to be required of it. In some stoves or heaters it 70 might be desirable to make it of such configuration as when erected to make a nearly tight or close partition between the two compartments of the fire-box. In such cases the plate C would be sparsely perforated; or where it 75 might be requisite or desirable to have communication between the two compartments to admit draft or otherwise, it could be perforated or slotted to the desired degree. Thus I have shown it in the drawings as both 80 wholly and partially perforated, and in those cases where the circulation of air is otherwise well provided for it need not be perforated at all for that purpose. The like suggestions hold good as to the degree of perforation of 85 the bottom of the ember sink or basin B. It must be determined by experience, the judgment of the constructor or operative, and the nature of the service required of it, and, as is well known, these constantly vary. 90

The rolling partition-plate is so constructed that its position may be reversed, so as to roll in the opposite direction or over toward the basin B. In such cases it could be so constructed as to entirely cover such basin, thus 95 making practically an extension of the upper plane, A, throughout the whole extent of the fire-box. This could be done without departing in any material respect from the general principles of construction of the several parts of the apparatus. Such disposition of parts would practically restore the old style of fire-box so far as a uniform fuel-supporting plane is concerned. In the latter case plate C would lie in a plane considerably above the bottom B of the ember-basin, and therefore it would not be material 105 whether the perforations of partition-plate C coincided with those of the bottom of plate B or not, as both draft and ashes would find free passage through the apertures in both plates. 110

Having thus described my invention, what I claim as new, and constituting the subject-matter for which these Letters Patent are granted, are the following novel features and combinations of parts, viz:

1. A horizontal fire-grate for use in stoves, ranges, and heaters, having a section of its fuel-supporting area constructed in a plane lower than the general plane of such area, so as to constitute a basin or receiver for embers or partially-consumed fuel, the bottom of which basin is perforated with a much less number of draft-apertures than the adjacent portions of the grate, as a means for conserving fuel when the fire is dying out, substantially as 120 specified.

2. A horizontal perforated fire-grate adapted to be used in the combustion-chambers of stoves, ranges, and heaters, in combination with a detachable partition-plate, substantially 125 as herein described, armed with hinge-lugs adapted to articulate with the perforations in 130

the fire-grate, whereby such partition - plate may be hinged to the fire-grate, substantially as described, and for the purposes set forth.

3. A horizontal fire-grate for use in stoves, ranges, and heaters, provided on its upper surface with a hinged perforated rolling partition-plate connected and adjusted as described, so that when erected it shall divide the fire-box into two compartments, between which draft circulation can be maintained through the perforations in said partition, and when recumbent such perforations shall coincide with the openings in the grate itself as a means for admission of air and escape of ashes, substantially as described and set forth.

4. The specific means shown for articulating the rolling partition-plate with the grate, consisting of the crank-shaped lug *b*, projecting from the edge of the rolling plate *C*, constructed with the stop-facets *e* and *f*, arranged at right angles with each other, or so that

when the plate is erected, one pair, *e e*, will prevent its further rotation away from the recumbent position, and when the plate is recumbent the other pair, *f f*, will so hold it locked 25 down in such position that it cannot be displaced, substantially as specified.

5. A horizontal perforated fire-grate for use in the fire-boxes of stoves, ranges, and heaters, provided with a detachable falling partition- 30 plate armed with hinge - lugs, the perforations of the grate and the hinge - lugs of the partition-plate being so adapted to each other that the position of the partition-plate may be reversed so as to fall in opposite directions in 35 the manner described, and for the purposes set forth.
